Primary Examiner — Lauren D McVey

(57) **CLAIM**

The ornamental design for a label printer, as shown and described.

DESCRIPTION

FIG. 1 is a first perspective view of a label printer design showing my new design.

FIG. 2 is a second perspective view of a label printer.

FIG. 3 is a third perspective view of a label printer.

FIG. 4 is a right view of a label printer.

FIG. 5 is a left view of a label printer.

FIG. 6 is a front view of a label printer.

FIG. 7 is a rear view of a label printer.

FIG. 8 is a top view of a label printer; and,

FIG. 9 is a bottom view of a label printer.

The broken lines shown in the drawings depict portions of the label printer in which the design is embodied that form no part of claimed design.
